UNITED STATES PATENT OFFICE.

HUGH D. ELLIOTT, OF SKAMOKAWA, WASHINGTON.

BELL-RINGING DEVICE.

1,136,781.

Specification of Letters Patent. Patented Apr. 20, 1915.

Application filed July 23, 1914. Serial No. 852,676.

To all whom it may concern:

Be it known that I, HUGH D. ELLIOTT, a citizen of the United States, and a resident of Skamokawa, in the county of Wahkiakum and State of Washington, have invented a new and Improved Bell-Ringing Device, of which the following is a full, clear and exact description.

My invention relates more particularly to a fog bell, in which a fixed bell is employed and is automatically sounded at predetermined intervals.

The prime object of the invention is to provide in association with the fixed bell, an independent, revolubly mounted clapper or striking device arranged to give a plurality of sounding strokes against the bell in any desired rapidity of succession, the striking periods occurring at the desired intervals.

In carrying out my invention, use is made of a clapper or striker mounted on a driven shaft turning beneath and adjacent to the bell, and the end of the clapper is hinged to be normally maintained, by centrifugal action, radial to the shaft, but yielding at its pivot or hinge to pass the bell. The clapper shaft is driven from an electric motor, in circuit with which is a circuit closer comprising relatively movable contact members, the alternate making and breaking of the circuit being effected through the medium of a ratchet wheel which engages by successive teeth with one of the contact members, to press the same against the coacting member, for closing the circuit, the member engaged by the tooth gravitating from the contact position as the tooth of the ratchet wheel permits said member to drop.

The invention will be more particularly explained in the specific description following.

Reference is to be had to the accompanying drawings forming a part of this specification, in which similar characters of reference indicate corresponding parts in all the views.

Figure 1 is a partly sectional side elevation of a bell and its bell-ringing means constructed and arranged in accordance with my invention; Fig. 2 is a side elevation of a circuit closer and switch employed in the circuit with the electric motor for actuating the bell-striking means; and Fig. 3 is a detail transverse section showing the clapper and bell.

In constructing a practical embodiment

of my invention in accordance with the illustrated example, to any suitable frame 10 a bell 11 is fixedly secured in any approved manner, as by a bolt or shank 12 and nut 13. Below and adjacent to the bell a shaft 14 is mounted in suitable bearings 15 on the frame 10. Secured to the shaft 14 is a radial arm 16, to the outer end of which is hinged a clapper 17, the hinge connection being established, in the present example, by a pivot pin 18, which passes through the shank of the clapper 17 and through the arm 16. To actuate the shaft 14 an electric motor 19 is provided, suitably geared to the said shaft. In the present example a bevel pinion 20 on the motor shaft meshes with a bevel gear wheel 21 on a vertical shaft 22, the opposite end of which is similarly provided with a bevel gear 23 which meshes with a bevel gear wheel 24 on the shaft 14.

In order that at predetermined intervals the shaft 14 be given a plurality of revolutions for causing the clapper 17 to rapidly strike the bell, I provide in the circuit with the motor, a circuit closer to automatically make and break the circuit. The circuit closer comprises a ratchet wheel 25 on a shaft 26, which in practice will be driven by a clock movement (not shown). Above the ratchet wheel a contact member 27 is pivotally supported, as at 28, on any suitable base or frame 29, and gravitates into contact with the toothed periphery of the ratchet wheel so as to be lifted by the successive teeth of the ratchet wheel, in the turning of the latter. The free end of the contact member 27 lies adjacent to and beneath a second contact member 30, which desirably is pivoted as at 31 to any suitable bracket or equivalent 32. The conductor wires are connected respectively to the pivot 28 and to the block 32.

By the described construction, in the rotation of the ratchet wheel 25, the teeth thereof will gradually raise the member 27 until it contacts with the member 30 to complete the circuit. Upon the engaging tooth of the ratchet wheel passing beyond a shoulder 27^a formed on the contact member 27, the latter will drop and break the circuit. By pivoting the second contact member 30, the latter will yield to the rising movement of the member 27 after the latter has made contact so that the circuit will be maintained closed sufficiently long to result in the motor 19 giving a plurality of revolu-

tions to the clapper shaft 14, and thus cause the clapper to strike the bell 11 a number of times in rapid succession before the breaking of the circuit. Thus the clapper will be actuated at intervals, which may be regulated according to the speed of rotation of the ratchet wheel, or the number of teeth. Any suitable switch 38, here conventionally shown, may be employed also in the circuit to manually open or close the circuit.

Having thus described my invention, I claim as new and desire to secure by Letters Patent:

1. In a device of the character described, a circuit closer, comprising a ratchet wheel, a contact member pivoted at one end and extending over the ratchet wheel, said contact member engaging the ratchet wheel intermediate of its ends, and a second pivoted contact member above the free end of the first contact member and with which the said free end engages when raised by the ratchet wheel.

2. In a device of the character described, a circuit closer comprising a contact member, a second contact member pivoted at one end and having its free end extending under the first member, the said second member having a shoulder on the underside intermediate of its ends, and a ratchet wheel, the teeth of which contact with the second member to move the same toward and from the first member, the engagement of the teeth of the ratchet wheel being adjacent to the shoulder of the second contact member to permit the said second member to have retrograde movement away from the first member upon the movement of a tooth beyond said shoulder.

In testimony whereof I have signed my name to this specification in the presence of two subscribing witnesses.

HUGH D. ELLIOTT.
